HEATING SYSTEM VALVE

Horace S. Kehm and Courtland G. Newton, Chicago, Ill.; said Newton assignor to said Kehm

Application September 14, 1940, Serial No. 356,760

14 Claims. (Cl. 277—1)

The present invention relates in general to a heating system and is particularly concerned with improvements in heating systems of the type wherein forced flow circulation of hot water is utilized for the transference of heat energy from a boiler to remotely located radiating means, and further contemplates novel means for improving the efficiency and operation of such systems. The present invention constitutes a continuation-in-part of our copending application Serial No. 275,044, now Patent No. 2,246,802, granted June 24, 1941.

In the Horace S. Kehm Patent No. 2,020,064, a heating system is illustrated and described, wherein heated water is circulated under pressure from a boiler through a single pipe main in the form of a loop to which a plurality of radiators are connected by supply and return risers respectively. At each radiator, the main constitutes a shunt or by-pass for the radiator, and the fittings by which the supply and return risers are connected to the main are so arranged that stratified flow of the water results in the main.

More specifically, during flow of water in the main between the radiators, the hot water bypassing a radiator will be delivered at the radiator return connection to the top portion of the main, and the somewhat cooled water returning from the radiator will be delivered to the bottom portion of the main. At the supply risers of the radiators, the connection fittings are arranged to take water from the upper portion of the main, the water at the lower portion of the main flowing through the radiator by-passes.

The system described in the aforementioned patent is very suitable and efficient in operation when utilized in relatively large heating systems in which the main loop is of relatively large diameter pipe. In small systems, however, such as would be installed in a small home and would usually contain eight or less radiators, the economical size of the main loop becomes so small that the advantages resulting from stratified flow of the water are lost or reduced to such an extent that the stratification of the water becomes impracticable.

Having in mind the unapplicability of a stratified system of flow for economic low cost installation of small heating systems, the present invention contemplates an improved connection fitting wherein efficient heating may be secured in a small single main loop heating system having a comparatively few radiators and a main line of relatively small diameter.

A further object of the present invention is to provide an improved connection fitting for a heating system which enables all the radiators to be furnished of the same standard size irrespective of the sizes of the rooms in which they may be installed, thus eliminating the cost of skilled engineering service for calculating and determining the various radiator sizes to meet different installation conditions.

Another object of the herein described invention is to provide an improved connection fitting for single loop heating systems which will enable the amounts of flow of heating fluid through the radiators to be successively graduated and increased as the temperature of the heated fluid is successively decreased by flow through the radiators.

Still another object is to provide an improved fitting that may be utilized in a looped main heating system to provide flow choking means at each radiator for controlling flow therethrough, and which is arranged to open whenever the fluid pressure in the main exceeds a predetermined amount.

Yet another object of the invention is to provide an improved fitting for connecting a radiator into the main of a loop type heating system, this fitting embodying an adjustable spring biased baffle means for choking flow through the fitting but operating upon predetermined increase of pressure in the heating system to move to ineffective position and thus relieve the system pressure and permit circulation through the system.

In accordance with the general features of the herein described invention, it is proposed to provide a novel connection fitting especially adapted for use in heating systems employing a single pipe main in the form of a loop to which the radiators are connected by supply and return risers. This loop is connected to a suitable furnace or device for heating the fluid, and the heated fluid is circulated under pressure by means of a suitable circulating pump. Either the supply or return risers of the radiators are connected into the main loop by means of the usual T-pipe fitting, and the radiators provided with the usual throttling valve. The risers of the respective radiators which are not connected by the usual T-pipe fitting are each connected to the main by means of a special T-fitting.

This special fitting, which is more fully described subsequently, is arranged with an adjustable baffle which serves as a choke or retarder for the water in the main which is by-

passed around each radiator. These baffles are arranged with adjusting means exteriorly of the fitting body so that the baffle may be adjusted to provide more or less choking or retarding effect as desired.

Since the conditioned fluid in this type of system is successively shunted through the radiators from the main loop the successive baffles or retarders may be successively closed by greater amounts so that as the conditioned fluid is gradually cooled by passing through radiators, the subsequent radiators will pass more fluid so that the heating capacity of all the radiators will be substantially equalized. Since the last radiator of the series will have its baffle almost fully closed, it will be apparent that if this radiator should be shut off by its throttling valve, circulation through the preceding radiators would be seriously effected and pressure would build up ahead of the last baffle.

As an additional feature, this baffle is arranged to be normally biased by a spring, so that when the pressure builds up ahead of it, the baffle will be opened independently of its adjusted position and relieve the pressure so that the circulation through the system may be continued efficiently.

Other objects and features of the invention will more readily appear from the following detailed description taken in connection with the accompanying drawings which illustrate several embodiments thereof, and in which:

Figure 1 is a view illustrating a single main loop heating system to which the present invention has been applied;

Figure 2 is an enlarged longitudinal section through one form of fitting construction embodying the present invention;

Figure 3 is a section through the same taken substantially on line III—III of Figure 2;

Figure 4 is a section taken substantially on line IV—IV of Figure 2;

Figure 5 is an exterior view in elevation of a different form of fitting construction;

Figure 6 is a longitudinal section taken through the same to show its internal construction; and

Figure 7 is a transverse sectional view taken through the fitting substantially on line VII—VII of Figure 5.

As shown on the drawings:

In the illustrated embodiment of the present invention there is shown in Figure 1 a boiler 10, which is connected at its outlet to one end of a single pipe main loop 11 and its inlet to the other end of the main loop. Interposed in the main loop is a suitable circulating pump 12 by means of which conditioned fluid may be circulated through the system, in this instance water which has been heated in the boiler.

A plurality of heat exchange devices, in this instance radiators as shown at 13, 14, and 15, are successively connected to the main line by means of supply and return risers 16 and 17. It will be noted that connection of the return riser is made to the main line by means of an ordinary T-fitting as shown at 18 and that each radiator at its connection with the supply riser is provided with a suitable control or throttling valve 19 by means of which the circulation of conditioned fluid through the radiator may be manually controlled.

Each supply riser 16 is connected with the main line by means of a T-fitting 20 or 20' having a construction which will be subsequently described in detail. In the disclosed arrangement,

it will be noted that the main line at each radiator in its portion lying between the fittings 18 and 20 or 20' forms a shunt flow circuit past the radiator.

5 In general, the fittings 20 or 20' are so arranged as to retard or choke the flow of fluid through the associated shunting portions of the main line, and this choking characteristic is made adjustable so that the amount of fluid forced through the associated radiator may be adjusted. Although the fittings 20 are herein shown as being connected in the supply riser, it will be understood that these fittings may be just as well connected in the return riser as shown in the aforementioned copending application.

Referring more specifically to the drawings, the construction disclosed in Figures 2, 3, and 4 shows a fitting having a T-shaped body structure 21 formed of any suitable material such as wrought iron, brass, and the like. This body is of hollow construction, as will hereafter be explained in detail, and is provided with a pair of main line connection openings 22 and 23, and also a branch connection opening 24, which may be angularly disposed with reference to the main line connection openings. The openings, if desired, may be internally threaded to facilitate the making of pipe connections thereto.

In the construction shown, the body is provided with an opening 25 in axial alignment with the branch opening 24. The opening 25 is internally threaded for receiving the threaded end of a plug member 26, which may be sealed relative to the body by means of a suitable gasket 27.

The interior of the body is cored to provide a generally cylindrical interior wall 28 having its longitudinal axis in alignment with the center line of the plug 26 and the branch opening 24. At the respective ends of the cylindrical walls, there are provided on opposite sides thereof the openings 29 and 30 which respectively establish communication with the main line opening 22 and the main line opening 23 through internal chambered portions 31 and 32.

45 The wall 28 is interiorly provided with annular spaced shoulders 33 and 34 for respectively receiving disk-like inserts 35 and 36, which respectively separate the branch opening 24 and the wall opening 29 from the opening 29 in the wall 28. In this construction, the inserts 35 and 36 further define an intermediate chambered portion 37, which is in communication through the opening 29 with the main line connection opening 22. The inserts 35 and 36 are maintained in proper spaced-apart relation by means of a pin member 38, which extends through and is rigidly secured to the respective inserts and has one end anchored in the plug 26.

60 The inserts 35 and 36 are respectively provided with segmental openings 39 and 40, which are relatively in diametric opposed relation, these openings providing small passages from the chamber 37 to the main connection opening 23 and the branch opening 24.

65 Means are provided for simultaneously controlling the size of the small passages through the openings 39 and 40 in such a manner that as one of the passages is constricted, the other is opened up. For such purpose, there is associated with the inserts segmental plate members 41 and 42, which are carried by a rotatable shaft 43 having bearing supports in the inserts and the plug 26. One end of this shaft extends through 70 the plug to the exterior of the fitting and is

sealed against leakage along the shaft by a suitable packing or gasket 44. The exteriorly disposed end of the shaft is formed with angularly disposed faces, as shown at 45, for receiving a suitable tool by means of which the shaft may be rotated.

It will be noted that the member 41 is disposed adjacent the inner surface of insert 35, whereas member 42 is disposed adjacent the outer surface of insert 36. As shown in Figures 3 and 4, the shaft 43, where it extends through the inserts, is provided with oppositely disposed flattened side portions 46 and 47, which interfit with suitably conformed openings at the center of the members 41 and 42 in such a manner as to prevent relative rotating movement of these members on the shaft, but permit longitudinal shifting of the members along the shaft and tilting thereof.

The member 41 is retained in pressure engagement with its associated insert by means of a coiled spring 48, which surrounds the shaft and has one end abutting the member 41 and its other end abutting the insert 36. Likewise, the member 42 is urged into engagement with the associated side of insert 36 by means of a coiled spring 49 surrounding the shaft and having one end bearing against the member 42 and its other end bearing against the packing 44. It will be noted that the spring 48 is relatively heavier than the spring 49. The spring 49 is so proportioned that during normal operation of the heating system in which this fitting may be installed, the member 42 is partially closed or regulating position over the opening 40 will be maintained against the associated insert. On the other hand, if at any time the pressure within the chamber 37 should increase above a predetermined amount, this pressure will act on the member 42 and force it into a tilted position, as shown in Figure 2, whereby its choking effect will be reduced and free flow of fluid through the opening 40 permitted.

In addition to maintaining the inserts 35 and 36 in spaced relation and preventing their rotation when the shaft 43 is rotated, the pin 38 also forms a stop for limiting rotative movement of the members 41 and 42 at their fully opened and fully closed positions in relation to the openings 39 and 40.

The construction previously described permits ready and easy inspection of the internal parts of the fitting, since the plug 26, shaft 43, and the associated inserts and members 41 and 42 may be removed as a unit with the plug 26 from the fitting body.

In the system shown in Figure 1, the radiators are disposed above the main loop of the heating system. In some installations it may be desirable to have the radiators connected below the loop, in which case the fittings just described would be disposed in inverted position. Under certain circumstances there might be a tendency for an air pocket to form in the then upwardly disposed portion of chamber 31. To prevent the formation of such a pocket, the wall 28 may be provided with a small bleeder passage 50.

The fitting 20', as shown in Figures 5, 6 and 7, comprises a T-shaped body structure 51, this body being constructed of any suitable material such as wrought iron, brass, and the like. The body structure defines an interior chamber 52 of substantially rectangular cross section. This chamber communicates with a pair of main

line connection openings 53 and 54 and also a branch connection opening 55 which may be angularly disposed with reference to the main line connection openings. These openings, if desired, may be internally threaded for pipe connection.

Within the chamber 52 there is disposed adjacent the main opening, which will be utilized for the inlet of fluid to the fitting, a baffle plate 56 having its uppermost edge margin provided with a barrel portion 57. The barrel 57 is rotatably mounted upon a transversely extending shaft or pivot pin 58 supported in the body structure for rotative movement, one end of this pin being disposed in a projecting portion 59 of the housing, and the other end being extended through an integrally formed tubular boss 60 on the opposite side of the body structure. Intermediate its ends, the boss 60 is provided with an internal shoulder 61 which forms an abutment seat for a washer 62 surrounding the shaft and serving to maintain it at the axis of the tubular boss. The outer end of the boss is threaded for threadedly receiving a cap member 63 which cooperates with the washer 62 in maintaining a suitable packing 64 compressed around the associated end of the pivot member 58 and thus prevent leakage of fluid from the fitting body along the pivot member.

The end of the pivot member which projects through the cap 63 is provided with a crank handle 65 by means of which the pivot member 58 may be rotated from the exterior of the fitting body.

Arrangement is made for maintaining the crank handle in any position of adjustment by providing a detent spring 66 having one end secured to the handle, and its other overlying and riding upon a curved rack 67 on the fitting body. This rack may be formed as a separate element and secured to the body or, if preferred, may be integrally formed on the body during its construction.

As shown in Figure 7, the right hand end of the barrel 57 is provided with a semi-circumferential end slot 68 in which there is disposed a pin 69 projecting from this end of the pivot member.

At the left end of the barrel 57, between this end of the barrel and the washer 62, there is provided a coil spring 70 which surrounds the pivot member. One end of this spring is anchored as at 71 to the shaft, while the other end of this spring is deflected so as to extend over and resiliently engage the innermost surface of the baffle 56 and normally move it in a clockwise direction as viewed in Figure 6, until this movement is stopped by the abutment of pin 69 against one end of the end slot 68.

With the foregoing construction, it will be apparent that the baffle plate 56 may be swung by means of the handle 65 to a position as shown in full lines in Figure 6, wherein it fully closes the opening 53 of the fitting and engages an abutment stop projection 72 at the bottom of the fitting, or the plate may be moved through an opening direction with reference to the opening 53 to a limiting position, as shown in dotted lines, in which the branch opening 55 will be fully closed or cut off from the chamber 52 within the fitting.

During the adjusting movement, the spring 70 is carried along with the rotative movement of the pivot pin 58. However, if pressure is applied against the outer surface of the baffle plate

56, the baffle plate may be independently swung on the pivot 58 against the pressure of spring 18, and thus automatically act as a relief valve with reference to the inlet opening 53.

Since the fittings 20 and 20' are, in each case, all similarly constructed, they may be indiscriminately utilized for connecting the risers from the radiators to the main line without consideration as to whether the radiator is the first radiator of the system or one of the subsequent radiators.

In utilizing our improved fittings in a heating system as shown in Figure 1, it will be appreciated that the flows through the successive radiators may be graduated and proportioned by adjustment of the respective fittings. That is, the fitting for the radiator 13 may be adjusted to substantially opened position, the fitting associated with the radiator 14 to a somewhat further closed position, and the last fitting to an almost fully closed position with reference to the main line of the system. Thus, as the conditioned fluid or heated water in this instance is circulated through the main line, the respective fittings operate to successively cause more fluid to be circulated through the associated radiators as the conditioned fluid becomes cooled.

Due to the fact that the fitting associated with the last radiator of the system—in this case the radiator 15—is almost fully closed, it will become apparent that should this radiator be shut off by closing its valve 19, all the water flowing through the main line must pass through the opening determined by the adjustment of its associated fitting. Since this fitting is almost fully closed, it is apparent that circulation of fluid in the main line would be seriously interfered with, and it would not be possible to efficiently operate the preceding radiators 13 and 14. However, this difficulty is automatically taken care of due to the relief feature of the fitting. That is, pressure will build up in the main line ahead of the fitting associated with the radiator 15, and when this pressure reaches a predetermined amount the fitting will automatically function as previously explained, and permit circulation of fluid through the system without passing through the radiator which is shut off.

Although the fittings 20 or 20' will in general be adjusted in the manner described above for successively determining the flow through the radiators accordingly as the temperature of the conditioning fluid is modified, the fittings are further advantageous in that they enable independent adjustment to compensate for the different resistances of the flow paths through the radiators and their connections.

Such differences in the resistance to flow through the radiators may arise from a number of causes. For example, the supply and return connections for one radiator may be of a different length than those of another radiator, or it may not be possible to utilize the theoretically proper size of pipe for the different radiators due to the standardization of pipe sizes.

Thus it will appear that not only is there a possibility of the last radiator of the system having its fitting adjustment substantially closed, but other radiators ahead of the last one might also under certain conditions have a considerable closure. Irrespective of which fittings may be substantially closed, these fittings will be relieved whenever the pressure builds up ahead of them to a predetermined amount, as might happen when their associated radiators are shut off. Ample system circulation will therefore always

be assured for the radiators remaining in operation.

While we have chosen to describe the present invention in connection with a heating system, we do not wish to be limited to such specific use, as it will readily be appreciated that the invention is susceptible of other uses and may be utilized advantageously, for example, in a cooling system.

10 From the foregoing description it will be apparent that the present invention provides an improved fitting particularly adapted for use with a heating or cooling system of the single main loop type; which is particularly adapted for economic installation where low cost is a factor as in small systems for homes and the like; which enables the installation of radiators of the same standard size irrespective of the heating requirements of the rooms in which the radiators are to be installed and without the necessity of the services of a skilled engineer to calculate various radiator sizes to meet the different installation conditions; which provides a system in which the amount of flow of heating fluid through the radiators may be successively graduated to provide increased flow as the temperature of the heated fluid diminishes; which is so arranged as to provide for relief operation whenever a radiator is shut off and the associated baffle or retarder is in such position as to prevent proper flow in the main line to efficiently operate the remaining radiators; and which provides an improved fitting for connecting the risers of the various radiators to the main line, this fitting embodying adjustable means for determining the circulation through the radiators with which the respective fittings are associated.

Now, it is of course to be understood that although we have described in detail several embodiments of our invention, the invention is not to be thus limited, but only in so far as defined by the scope and spirit of the appended claims.

We claim as our invention:

1. A pipe fitting comprising a body having an interior chamber, a plurality of flow passageways communicating with said chamber, adjustable valve members for proportioning outward flow from the chamber through two of said passageways, one of said valve members being mounted for independent movement under abnormal flow pressure in its associated passage to a pressure relieving position, and means resiliently opposing said independent movement under normal pressure conditions.

2. A pipe fitting comprising a body having an interior chamber, a plurality of flow passageways communicating with said chamber, simultaneously adjustable valve members for proportioning outward flow from the chamber through two of said passageways, one of said valve members being mounted for independent movement under abnormal flow pressure in its associated passageway to a pressure relieving position, and means resiliently opposing said independent movement under normal pressure conditions.

3. A pipe fitting comprising a body having an interior chamber, a plurality of flow passageways communicating with said chamber, rotatably adjustable valve members for proportioning outward flow from the chamber through at least two of said passageways, and means supporting one of said valve members for tilting movement under abnormal flow pressure in its associated passageway to a pressure relieving position, and

means for normally retaining said one of the members against said tilting movement.

4. A pipe fitting comprising a body having an interior chamber, an inlet to said chamber, a pair of outlet passageways from said chamber, a pair of valves for controlling flow through the outlet passageways, and common means for simultaneously adjusting the positions of said valves relative to their associated passageways, one of said valves being a relief valve.

5. A pipe fitting comprising a body having an interior chamber, an inlet to said chamber, a pair of outlet passageways from said chamber, a pair of valves for controlling flow through the outlet passageways, common means for simultaneously adjusting the positions of said valves relative to their associated passageways, one of said valves being a relief valve, and a bleeder by-pass around said one of said valves.

6. In a pipe fitting, a body structure defining an interior chamber having a pair of spaced wall forming portions in parallel relation, each of said portions having an opening therein defining an outlet from said chamber, an inlet to said chamber, a shaft rotatably supported in the wall portions, a first plate member carried by the shaft for face engagement with the inner surface of one of the wall portions, a second plate member carried by the shaft for face engagement with the outer surface of the other wall portion, said plate members being movable by the shaft into open and closed relation with the respective openings, means mounting said second plate member for movement away from its associated wall portion, and means resiliently opposing said latter movement.

7. In a pipe fitting, a body structure defining an interior chamber, a pair of aligned spaced inserts on opposite sides of said chamber, each of said inserts having an opening therein defining a flow outlet from the chamber, a flow inlet to the chamber, a shaft rotatably supported in the inserts and extending to the exterior of the body structure, valve members carried by said shaft for rotation therewith but axially movable thereon, one of said members being disposed adjacent the inner face of one insert and the other adjacent the outer face of the other insert for respective cooperation with the openings of the inserts to control the flow therethrough, and means resiliently urging the valve members towards their associated inserts.

8. In a pipe fitting, a body structure defining an interior chamber, a pair of aligned spaced inserts on opposite sides of said chamber, each of said inserts having an opening therein defining a flow outlet from the chamber, a flow inlet to the chamber, a shaft rotatably supported in the inserts and extending to the exterior of the body structure, valve members carried by said shaft for rotation therewith but axially movable thereon, one of said members being disposed adjacent the inner face of one insert and the other adjacent the outer face of the other insert for respective cooperation with the openings of the inserts to control the flow therethrough, and springs respectively urging the valve members towards their associated inserts, the spring associated with said other valve member being relatively the weaker.

9. In a pipe fitting, a body structure defining an interior chamber, a pair of aligned spaced inserts on opposite sides of said chamber, each of said inserts having an opening therein defining a flow outlet from the chamber, a flow inlet to

the chamber, a removable plug in the body structure, a shaft rotatably supported in the inserts and plug and extending through the plug to the exterior of the body structure, valve members carried by said shaft for rotation therewith but axial movement thereon, one of said members being disposed adjacent the inner face of one insert and the other adjacent the outer face of the other insert for respective cooperation with the openings of the inserts to control the flow therethrough, and means resiliently urging the valve members towards their associated inserts.

10. In a pipe fitting, a body structure defining an interior chamber, a pair of aligned spaced inserts on opposite sides of said chamber, each of said inserts having an opening therein defining a flow outlet from the chamber, a flow inlet to the chamber, a removable plug in the body structure, a shaft rotatably supported in the inserts and plug and extending through the plug to the exterior of the body structure, valve members carried by said shaft for rotation therewith but axially movable thereof, one of said members being disposed adjacent the inner face of one insert and the other adjacent the outer face of the other insert for respective cooperation with the openings of the inserts to control the flow therethrough, means resiliently urging the valve members towards their associated inserts, and means interconnecting the plug and inserts, whereby all of the parts may be removed with the plug from the body as a unit.

11. A fitting comprising a hollow body having an interior chamber, a plurality of flow passageways communicating with said chamber, adjustable valve means for at least two of said passageways, and resilient means opposing movement of said valve means when the flow pressure in said chamber is below a predetermined value and permitting movement of said valve means when the pressure exceeds said predetermined value for changing the rate of flow through the passageways associated with said valve means.

12. A fitting comprising a hollow body defining an interior chamber, a plurality of flow passageways communicating with said chamber, adjustable valve members in at least two of said passageways, and means sensitive to pressure within said chamber for regulating said valve members and proportioning outward flow from the chamber through the passageways associated with said valve members.

13. A fitting comprising a hollow body having a plurality of flow passageways from the interior thereof, an adjustable valve member in each of at least two of said passageways, and means for normally maintaining said valve members in a predetermined position relative to their respective passageways, said valve members being responsive to a difference in pressure on opposite sides thereof whereby they are moved from said predetermined position.

14. A fitting comprising a hollow body defining an interior chamber, a plurality of flow passageways communicating with said chamber, aligned inserts on opposite sides of said chamber, each of said inserts having an opening therein defining a flow outlet from the chamber, a removable plug in said hollow body, a non-circular shaft having portions rotatably supported in the inserts and plug and extending through the plug to the exterior of the body structure for manual actuation, means sealing said shaft in said plug against fluid flow thereby, valve members hav-

ing openings therein of generally the same shape as the cross-section of said shaft for receiving the latter therethrough, said valve members being carried by said shaft for rotation therewith and for axial movement thereon, one of said valve members being disposed adjacent the inner face of one insert and the other of said valve members being disposed adjacent the outer face of the other insert for cooperation with the openings in the inserts to control flow there- 10

through, springs respectively urging the valve members axially on said shaft and towards their associated inserts, one of said springs being relatively weaker than the other spring, and means 5 interconnecting the plug and inserts whereby all of the parts may be removed with the plug from the body as a unit.

HORACE S. KEHM.
COURTLAND G. NEWTON.
